UNITED STATES PATENT OFFICE

EDWARD J. BRANDT, OF WATERTOWN, WISCONSIN, ASSIGNOR TO BRANDT AUTOMATIC CASHIER COMPANY, OF WATERTOWN, WISCONSIN, A CORPORATION OF WISCONSIN

MONEY HANDLING MACHINE

Application filed January 11, 1929. Serial No. 331,859.

My invention relates to new and useful improvements in money handling machines in which a plurality of stacks of coins of different denominations are supported in a tray or the like and adapted to be ejected by the operation of keys bearing designating marks to indicate the amount of the coins to be ejected.

The principal object of the invention resides in the provision of a machine of the character described which is relatively simple and inexpensive in construction and of a size and shape adapting it to be used in a relatively small space, the height of the machine being relatively greater than the horizontal area whereby a relatively small area is required for support.

Another object of the invention consists in the provision of novel means for operating the fingers which eject the coins from the stacks, said operating means including a plurality of vertically spaced swinging plates and vertically extending members or bars which are operable by the keys, said vertically extending members or bars having substantially horizontally extending projections overlying the vertically spaced swinging plates and adapted to swing said plates upon operation of the bars by the keys, each of the vertically extending members or bars having the desired number of substantially horizontally extending projections to operate those swinging plates which will operate in turn the desired ejecting fingers for ejecting the coins from the stacks to an amount designated by the particular key operated.

A further object of the invention consists in the provision of novel means whereby the coins ejected may be delivered towards either end of the machine for delivery therefrom into a cup or receptacle, said cup or receptacle having a slidable bottom or door adapted to be operated so that the coins may be received in the hand of the operator, the cup or receptacle being detachably connected to the machine and adjustable whereby it may be secured to either end of the machine and positioned for operation from either the front or back of the machine.

50 A still further object resides in the pro-

vision of novel means for securing a substantially horizontally extending arm to each of the above mentioned swinging plates, said arms, when the plates are swung, causing operation of the coin ejecting fingers through suitable connecting means.

With the above and other objects in view, which will appear as the description proceeds, my invention consists in the novel details of construction and arrangement of parts described in the following specification and illustrated in the accompanying drawings, and while I have illustrated and described the preferred embodiments of the invention, as they now appear to me, it will be understood that such changes may be made as will fall within the scope of the appended claims.

In the drawings:—

Fig. 1 is a side elevation.

Fig. 2 is a front elevation with a portion of the coin supporting tray broken away.

Fig. 3 is a transverse vertical section on the line 3—3 of Fig. 2 looking in the direction of the arrows.

Fig. 4 is a longitudinal vertical section on the line 4—4 of Fig. 3 looking in the direction of the arrows.

Fig. 5 is a horizontal section on the line 5—5 of Fig. 3 looking in the direction of the arrows.

Fig. 6 is a fragmental longitudinal section on the line 6—6 of Fig. 3 looking in the direction of the arrows.

Figs. 7 and 8 are enlarged details, partly in section and partly in side elevation of the mechanism for operating the coin ejecting fingers; and

Fig. 9 is a detail perspective of a portion of one of the swinging plates showing more particularly the manner of connecting the arm thereto.

In the drawings 1 indicates the bottom plate, 2 the back plate, 3 and 4 the side plates, and 5 the front plate of the machine, the front plate including the downwardly and outwardly inclined portions 6 having a plurality of spaced openings through which the key bars, to be later described, extend. The machine as an entirety is supported by

the feet 7, which are preferably made of rubber or similar material so as not to mar the object upon which the machine is supported, and the plates 1, 2, 3, 4 and 5 are secured to an interior frame structure, but as this frame structure forms no particular part of the present invention a detail description thereof is not thought necessary. Secured within the machine, and extending parallel with the front plate 5, are the plates 7 and 8 which are spaced apart, as shown more particularly in Figs. 3 and 5 of the drawings, to receive the inclined chute 9 which receives the coins delivered from the coin tray and directs them through the side 10 or end of the machine into a cup or receptacle to be later described. This chute is of a construction and supported in such a manner that it is reversible to direct the coins towards either side or end of the machine. At its upper end the chute is formed with a substantially horizontally extending flange adapted to rest upon the top edge of a plate 11, one of these plates 11 being secured to each side or end of the machine, as shown more particularly in Fig. 4 of the drawings. The lower end of the chute extends through an opening formed in the end or side plate. In the drawings I have illustrated the lower end of the chute as passing through an opening 12 formed in the side or end plate 3 but the plate 4 is provided with a similar opening 13 through which the lower end of the chute will extend when the position of the chute is reversed to discharge the coins through the side or end 4. A plate 14, as shown, is secured over the opening 13 by means of the screws 15 or other suitable fastenings and when the position of the chute, shown in Fig. 4, is reversed to deliver the coins through the opening 13 it will be understood that the plate 14 will be detached and secured over the opening 12. It will thus be seen that that opening not in use is closed by the plate 14 and this plate may be in the form of a name plate or the like. Secured to the underside of the chute 9 is the bracket member 16 which is adapted to be detachably connected, by means of the screw 17 or other suitable fastening, to the inverted U-shaped bracket 18 which extends between and is secured to the plates 7 and 8. By means of this connection the chute 9 is held against accidental displacement and the bracket member 16 and bracket 18 are of a construction whereby the position of the chute may be reversed, as has been previously described, to discharge the coins towards either end or side of the machine.

A housing 19 is secured to that end or side of the machine through which the coins are adapted to be discharged, by means of the screws 20 or other suitable fastenings and this housing is open at the top, bottom and back, the back opening being adapted to

align with the opening in the side or end to which the housing is attached. In the drawings I have illustrated in full lines the housing as being secured to the plate 3 at the left hand side or end of the machine and, as shown more particularly in Fig. 5 of the drawings, the lower end of the chute 9 extends through the opening 12 in the plate 3 and through the back opening of the housing. It will be understood that if the chute 9 is positioned to discharge the coins through the opposite end or side of the machine that the plate 14, which is shown as covering the opening 13 in the plate 4, will be removed and the housing 19 secured in its place. The plate 14 will then be secured to the side or end plate 3 to cover the opening 12 therein. A cup 21 is adapted to be connected to the housing 19 by means of the screw 22 or other suitable fastening. The cup 21 is provided at the top with a flange 23 which fits within the bottom opening of the housing, as shown more particularly in Fig. 4 of the drawings and the screw 22 passes through the housing and engages with the flange to hold the cup in position. By loosening the screw 22 the cup may be detached from the housing or swung relative thereto. Secured to the lower end of the cup is an elongated frame structure 24 which slidably supports the bottom member 25 of the cup, this bottom normally closing the bottom of the cup and supporting the coins discharged therein. The bottom 25 is provided with a depending ledge or flange 26 which is adapted to be engaged by the operator for sliding the bottom in the frame 24 and allow the discharge of the coins into the hand of the operator. The bottom is normally held in its closed position by means of a coiled spring, not shown, received in the sleeve 27. At one end the bottom 25 is provided with the upstanding projections 28 which at times may be engaged by the operator for operating the bottom and these projections are also adapted for engaging the bumpers 28' carried by the end of the frame 24. The normal position of the cup and frame is shown by full lines in the drawings but, when desired, may be positioned, as shown in dotted lines more particular in Fig. 1 of the drawings, whereby the slideable bottom may be operated by a person standing at the rear of the machine. The frame 24 is provided with notches 29 adapted to be engaged by a latch member, not shown, controlled by the lever 30 whereby the bottom may be held, when desired, in its open position. From the above it will be seen that the cup for receiving the coins may be connected to either side or end of the machine by interchanging the housing from one side to the other and the cup may be so positioned by adjusting the same relative to the housing that the slideable bottom thereof may be operated by a person standing either in front or back of the machine. By dotted lines

in Fig. 2 of the drawings I have shown the housing and cup in position on the right hand side of the machine.

A tray for the stacks of coins is supported on the ledge 31 formed at the top and as a part of the plate 8 and rests against the up-standing portion 32 which forms a part of the front of the machine. The tray consists of the back, 33, bottom 34 and vertically extending partitions 35 which form the compartments 36, 37, 38, 39, 40, 41, 42 and 43. Flanges 44 extend rearwardly from the back 33 and engage the top 45 of the machine, these flanges being engaged by the latch members 46 for holding the tray in position. Feet members 47 also extend rearwardly from the tray and engage the top 45, cooperating with the flanges 44 for supporting the tray in position. Pins or projections 48 extend upwardly from the ledge 31, which supports the tray, and extend through openings formed in the bottom 34 of the tray, these pins or projections holding the bottom of the tray in position. As the specific construction of the tray forms no particular part of the present invention a further detail description thereof is not thought necessary. Longitudinally spaced openings 49 are formed in the front portion 32, against which the tray rests, and longitudinally spaced openings 50 are formed adjacent the bottom of the back 33 of the tray and register with the openings 49, pusher or ejector fingers, to be later described, operating through these openings for ejecting the coins from the tray. A stack of fifty cent pieces is adapted to be received in the compartment 36, a stack of quarters in the compartment 37, stacks of 10¢ pieces in the compartments 38 and 39, a stack of 5¢ pieces in the compartment 40, and stacks of pennies in the compartments 41, 42 and 43. It will be understood that the lowermost coin in each stack will rest upon the bottom of the tray, as shown more particularly in Fig. 3 of the drawings, and longitudinally spaced recesses 51 are formed in the bottom, in alignment with the openings 50, to allow for proper operation of the pusher fingers, to be later described, in the ejecting operation.

Supported between the sides of the machine, adjacent the back thereof and spaced from the bottom, is a horizontally extending rod 52 on which are pivotally mounted the rear ends of a plurality of key bars 53 having the upwardly extending portions 54, at the front end, which project through openings formed in the inclined portion 6 of the front. A finger piece 55 bearing a designating mark indicating the amount of the coins to be ejected from the tray is secured or formed on the end of the upwardly extending portion 54 of each of the key bars. The key bars are held in normally raised position by means of the coiled springs 56, the lower ends of the

springs being secured to their respective key bar while the upper end thereof is engaged with a hook 57 formed on the longitudinally extending plate 59 which is secured to the plate 8 by means of the screws 59 or other suitable fastenings. The manner of connecting the springs 56 is shown more particularly in Figs. 3 and 4 of the drawings. Positioned between and secured to the sides of the machine is a plate 60 which extends parallel with the rod 52, this plate being formed at the top with the flange 61 and at the bottom with a rearwardly directed flange 63. Longitudinally spaced recesses 64 are formed in the plate 60 and these recesses also extend through the flange 63, as shown more particularly in Fig. 3 of the drawings. The flange 63 extends beneath the rod 52 and the upper portions of the key bars 53 extend into the recesses as shown. The plate 60, with the recesses, properly spaces the key bars on the rod 52. Secured to and extending upwardly from the bottom 1 of the machine is a plate 65 which has longitudinally spaced recesses or notches 66 extending downwardly from the top thereof and in alignment with the recesses 64 formed in the plate 60. The forward ends of the key bars 53 operate in the recesses or notches 66 which act as guides therefor and properly space the forward ends of the key bars.

Secured to and extending between the sides of the machine is a horizontally extending plate 67 having a plurality of notches formed in its rear edge to provide guides for the vertically extending bars 68 adjacent the upper ends thereof. The lower end of each of the bars 68 is pivotally connected at 69 to a key bar 53 and adjacent the upper end each of the bars 68 is formed with an elongated opening 70 through which extends a horizontal rod 71 which is supported by and extends between the sides. This rod 71 engaging opposite ends of the recess 70 acts to limit the movements of the bar 68. Each of the bars 68 is provided with one or more forwardly extending projections 72, the bars shown more particularly in Fig. 3 being illustrated with five such projections for a purpose to be later described. Each of the bars 68 is also provided with a plurality of curved recesses 73 formed in its forward edge for a purpose which will also be later brought out.

Pivotaly mounted for swinging movement between the sides of the machine are the vertically spaced members 74, 75, 76, 77, 78, 79, 80 and 81 which are adapted to be engaged and operated by the forwardly extending projections 72 on the bars 68. Secured to each of the members 74, 75, 76, 77, 78, 79, 80 and 81 is a rearwardly directed arm 82. Each of the arms is formed with a right angle projection or lug 83 which is secured to the bottom of the member by means of the rivets 84 or other suitable securing means and

each of the members is provided with a slot 85 into which a portion of the arm extends. The construction of the arms and the manner in which they are secured to the swinging members is shown more particularly in Fig. 9 of the drawings.

Depending from the horizontally extending rod 86 are the swinging levers 87, the upper ends of which pass through slots 10 formed in the plate 88 which has the downwardly extending flange 89. A coiled spring 90 is secured to each of the levers 87 and normally hold the levers in their rearward-most positions, as shown more particularly 15 in Fig. 3 of the drawings. One end of each of the coiled springs is secured to its associated lever while the opposite end is secured to the flange 89 on the plate 88. The swinging movement of the levers is limited by the 20 abutments 91 and 92 which may be made of fibre or the like to take up jar and to deaden the sound of contact. Extending rearwardly from each of the levers 87 is an arm 93 and a link 94 connects each of the arms 93 with 25 one of the arms 82 of the swinging members 74, 75, 76, 77, 78, 79, 80 and 81. Therefore as the members are swung they will operate that swinging lever 87 which is connected thereto.

30 Pivotedly connected at 95 to each of the levers 87 is a pusher or ejecting finger 96, these fingers having their forward ends extending through the aligned openings 49 and 50 of the coin tray and rest therefor, as 35 shown more particularly in Fig. 3 of the drawings, to engage the edge of the coin or coins. Coiled springs 97 are secured to and positioned between the lower ends of the levers and the rear ends of the pusher or 40 ejecting fingers 96 to normally hold the forward ends of the pusher or ejecting fingers in their raised position to properly engage the edge of the coin or coins. As the levers 87 are swung forwardly the fingers 96 will 45 eject the coin or coins from the stacks and they will be lowered in their movement to be received and operate in the recesses 51.

50 As shown there are eight stacks of coins and eight swinging members denoted by the numerals 74, 75, 76, 77, 78, 79, 80 and 81 and a pusher or ejecting finger for each stack, each of the swinging members controlling the operation of a pusher or ejecting finger. In 55 other words when one of the swinging members is operated coins will be ejected from a particular stack.

50 From the above detailed description it is thought that the construction will be perfectly clear and I will now endeavor to point out more in detail the manner of operation. As has been stated, the machine is adapted for ejecting from the tray coins to the amount indicated upon the keys. In Fig. 5 of the 65 drawings the indicating numerals are shown upon the keys. The key to the extreme right

of the first row, or lower row of keys has the indicating mark "100" thereon and by depressing this key \$1.00 in change will be ejected from the coin tray. In following the operation attention is directed more particularly to Fig. 3 of the drawings. When the key bearing the designating mark "100" is depressed it will lower the corresponding key bar 53 which will swing on the horizontal rod 52. The downward movement of the key bar will draw on and extend the coiled spring 56 and at the same time will draw the vertically extending bar 68 downwardly. As is shown in Fig. 3 of the drawings the vertically extending bar 68 has five forwardly extending projections 72 which overlie the swinging members 77, 78, 79, 80 and 81. Therefore when the bar 68 is drawn downwardly it will swing the frames 77, 78, 79, 80 and 81 downwardly with their respective arms 82 which in turn will draw downwardly on the connecting links 94 connected therewith and these links in turn will swing the levers 87 forwardly with the coin pusher or ejecting fingers 96. The swinging members 77, 78, 79, 80 and 81, respectively, operate the ejecting mechanism to eject coins from the stack of 5¢ pieces, the two stacks of 10¢ pieces, the stack of 25¢ pieces and the stack of 50¢ pieces. Therefore upon operation of the key bar bearing the indicating mark "100" one 5¢ piece, two 10¢ pieces, one 25¢ piece, and one 50¢ piece will be ejected from the coin tray or in other words a combination of coins amounting to \$1.00. As stated, the pusher or 100 ejecting finger 96 will force the coins from their respective stacks and the same will drop upon the inclined chute 9 and be delivered into the coin receiving cup 21 and rest upon the slidable bottom 25 thereof. The operator, 105 or other person to receive the change, then engages the ledge or flange 26 of the slidable bottom and pushes the same so that the coins will drop therefrom into the hand of the operator. When the key is released the key bar will be drawn upwardly or returned to its original position by means of the coiled spring 56. When the other keys are operated they will act to eject coins from the tray in 110 the same manner as above described, but, of course, it will be understood that different combinations of coins will be delivered or ejected according to the number of swinging members which are operated with their associated parts, it being understood that each of the vertically extending bars 68 will have a 115 different number of projections thereon or a different combination of projections. For instance, in Fig. 8 of the drawings I have illustrated the vertically extending bar 68 as having only a single forwardly extending projection 72 thereon and this overlies the swinging member 77. Therefore when the key bar connected to this particular vertically 120 extending bar 68 is operated the single pro-

jection thereof will swing the member 77 to eject only a single 5¢ piece from the stack of 5¢ pieces. As previously stated, each of the vertically extending bars 68 will have a different number of projections 72 thereon or a different combination of projections which overlie the swinging members and the swing-members which will be operated to eject the coins from the tray will depend upon the 10 number of projections on the particular vertically extending bar 68 which is operated. As an example if the key bearing the designating numeral 5, in the lower row of keys, is operated the swinging member 77 will be operated to eject a single 5¢ piece from the compartment 40 of the coin tray. If the key, bearing the designating mark 15 is depressed, a 10¢ piece and a 5¢ piece will be ejected, respectively, from the compartments 39 and 40 20 of the coin tray by the operation of the swinging members 77 and 78. Should the key bearing the designating mark 25, in the lower row of keys, be operated a single 25¢ piece will be ejected from the compartment 37 of the coin 25 tray by operation of the swinging member 80. Should either of the keys bearing the designating mark 1, in the top row of keys, be operated a single penny will be ejected from the stack of coins in the compartment 43 of the 30 tray by operation of the swinging member 74. Should either of the keys in the top row of keys bearing the designating mark 2 be operated two pennies will be ejected from the stack in the compartment 42 by operation of 35 the swinging member 75. Should either of the keys, in the top row, bearing the designating mark 3, be operated a single penny will be ejected from the stack in the compartment 43 and two pennies will be ejected from the 40 stack in the compartment 41 by operation of the swinging members 74 and 76 respectively. Should either of the keys in the top row bearing the designating mark 4 be operated two pennies would be ejected from each of the 45 stacks 41 and 42 in the compartments of the coin tray by operation of the swinging members 75 and 76. If the key bearing the designating mark 5, in the top row of keys should be operated, one penny would be ejected from 50 the stack in the compartment 43 of the tray and two pennies would be ejected from each of the compartments 41 and 42 by operation of the swinging members 74, 75, and 76, this making a total of five pennies to be ejected. 55 If the key bearing the designating mark 25 in the top row of keys is operated 25¢ in change would be ejected from the coin tray. By operation of the key mentioned bearing the designating mark 25 would cause ejection 60 of a 10¢ piece from the stacks of 10¢ pieces in the compartments 38 and 39 and a 5¢ piece from the stack of 5¢ pieces in the compartment 40, the coins being ejected by operation of the swinging members 77, 78 and 79. The 65 operation of this particular key differs from

the operation of the 25¢ key in the lower row of keys in that when the last mentioned key is operated only a single 25¢ piece is ejected. When the key bearing the designating mark "50" between the keys bearing the designating marks "40" and "60" is operated a single 50¢ piece will be ejected from the compartment 36 in the coin tray by operation of the swinging member 81. When the key bearing the designating mark 50, at the end of the middle row of keys, is operated 50¢ in change will be ejected from the coin tray. The operation of this particular key will eject a 25¢ piece from the compartment 37, a 10¢ piece from each of the compartments 38 and 39, and a 5¢ piece from the compartment 40 by operation of the swinging members 77, 78, 79 and 80. From the above examples given it is thought that the operation of the various keys will be understood as well as the amount of coins to be ejected through such operation. It will be noted that in the top row of keys there are two keys bearing each of the designating numerals 1, 2, 3 and 4 and either of the keys bearing the designating numerals 90 may be operated for ejecting the amount indicated thereon it being observed that upon the operation of these keys only pennies are ejected. By providing the double arrangement in the top row greater latitude in operation is given and either the right or left hand of the operator may be used for ejecting the desired combination of pennies. The fingers that eject the coins from the several stacks are so positioned that but a single coin 95 will be ejected at a time from each of the stacks with the exception of the stacks of pennies in the compartments 41 and 42. Two pennies will be ejected from each of these 100 stacks at a time, the ejecting fingers for these 105 stacks being on a somewhat higher plane than the others.

The vertically extending bars 68 are provided with the notches 73 so as to leave room for the operation of the swinging members. These are provided so that as the swinging members are swung downwardly there will be no danger of contacting with the edges of the bars as might be the case if the edges were left perfectly straight without the notches. 110

As has been previously described, the chute 9 is reversible so that the coins may be delivered to either side or end of the machine and the coin receiving cup with the supporting housing may be connected to either side or end of the machine and the cup may be swung relative to the housing so that the slideable bottom thereof may be operated from either the front or back of the machine. 115

The machine constructed as I have described is simple and compact in form and may be supported on a relatively small area, the parts being so formed and adapted that the machine will be of greater relative height 120

than width or depth so that, as stated, only a small area is needed for support.

Having fully described my invention what I claim as new and desire to secure by Letters 5 Patent is:

1. A money handling machine of the character described including a key bar, a substantially horizontally extending swinging member, a bar extending upwardly from the 10 key bar and connected thereto, a projection carried by the upwardly extending bar and overlying the swinging member to operate the same upon operation of the key bar, an arm extending from the swinging member, a 15 swinging lever hung from a horizontal axis and depending therefrom, an arm extending from the lever, means connecting the arm of the swinging member and the arm of the lever, and a coin ejector carried by the lever.

2. A money handling machine of the character described including a key bar, a substantially horizontally extending swinging member, a bar extending upwardly from the key bar and connected thereto, a projection 25 carried by the upwardly extending bar and overlying the swinging member to operate the same upon operation of the key bar, an arm extending from the swinging member, a lever hung from a horizontal axis in substantial 30 alignment with the upwardly extending bar and with its lower end terminating above the upper end of the bar, an arm extending from the lever, means connecting the arm of the swinging member and the arm of the lever, and a coin ejector carried by the lever.

3. A coin handling machine of the character described including a key bar, a member pivotally mounted on a horizontal axis for vertical swinging movement, a vertically extending bar pivotally connected at one end to the key bar and having an elongated opening adjacent the opposite end, said vertically extending bar extending to a position adjacent the swinging member, a projection extending 45 from the vertically extending bar and overlying the swinging member to operate the same upon operation of the key bar, means engageable in the elongated opening of the vertically extending bar for guiding and limiting 50 the movement thereof, a coin ejector, and means connecting the swinging member and coin ejector.

4. A coin handling machine of the character described including a plurality of key 55 bars, vertically spaced members pivotally mounted on horizontal axes for vertical swinging movement, a vertically extending bar pivotally connected to each of the key bars and extending to a position adjacent the 60 swinging members, each of the vertically extending bars having an elongated opening therein and the openings of the several bars being in alignment, means extending through the aligned openings of the vertically extending bars for guiding and limiting the 65

movements thereof, one or more projections extending from each of the vertically extending bars and overlying one or more of the swinging members to operate the same upon operation of the key bars, a plurality of coin ejectors, and means connecting each of the swinging members with a coin ejector.

5. A coin handling machine of the character described including a key bar, a member pivotally mounted on a horizontal axis for vertical swinging movement, said member having a slot extending from one edge thereof, an arm having one end extending into the slot of the swinging member and a horizontally extending lug extending beneath the member, means extending through the member and lug for securing the arm to the member, a coin ejector, means connected to the arm carried by the swinging member for connecting the swinging member and coin ejector, and means operable by the key bar and engageable with the swinging member for operating the swinging member and in turn the coin ejector.

In testimony whereof I hereunto affix my signature.

EDWARD J. BRANDT.
